UNITED STATES PATENT OFFICE.

WILLIAM H. JOSLIN, OF SOUTH SCITUATE, RHODE ISLAND.

BOX.

Application filed March 5, 1920. Serial No. 362,515.

To all whom it may concern:

Be it known that I, WILLIAM H. JOSLIN, a citizen of the United States, and resident of South Scituate, in the county of Providence and State of Rhode Island, have invented certain new and useful Improvements in Boxes, of which the following is a specification.

This invention relates to an improvement 10 in a box or casing adapted more particularly for the display of goods on a stand, counter or other exposed position; and the object of this invention is to provide such a casing with an inner receptacle, and means 15 for supporting this inner receptacle in an inclined position in said box to render more attractive and better display the goods carried thereby.

The nature and advantages of the invention 20 will be better understood when the following detail description is taken in connection with the accompanying drawings, the invention residing in the combination and arrangement of parts as claimed.

25 In the drawings forming part of this specification, like numerals of reference indicate similar parts in the several views and wherein:—

Figure 1 is a perspective view showing 30 the cover of the box open and the inner receptacle set on an incline in the outer casing.

Figure 2 is a side elevation illustrating 35 the inner receptacle as set on an incline, its raised edge being supported on an inwardly projecting lip formed integral with the wall of the outer casing.

Figure 3 is a sectional side elevation showing 40 the relative positions of the rear walls of both the inner and outer casings, also indicating in dotted lines the engaging position of the supporting lip.

Figure 4 is a view of the rear wall of the outer casing, illustrating one form of supporting lip therein.

With reference to the drawings, 10 designates one form of a display box or casing in which is mounted a separate and independent receptacle 11, which in this particular case, occupies the middle portion of this casing.

It is found in practice to be of advantage 55 in displaying goods carried by this box or casing that the inner receptacle should be raised or set at an angle or inclination

within the main casing; and in order to accomplish the supporting of this inner receptacle in its raised or inclined position, I have cut the rear wall 12 of the receptacle on a curve as at 13, see Figure 4, to provide 60 a lip 14, the upper edge of which is adapted to be bent inwardly from the plane of its wall to provide a rest or support for the edge portion 15 of this inner receptacle.

When the inner receptacle is shaped to 65 fit closely between the rear wall 12 and the front wall 16 of the outer casing, it is found that the tipping or setting of the inner receptacle on an incline necessitates the yielding or bending of the upper edge 70 17 of this front wall 16, as illustrated in Figures 1 and 2, owing to the fact that this inner receptacle when so set on an angle, takes up more space than when set squarely 75 into the outer casing. Therefore when the 80 inner receptacle is set at the desired incline the outward spring of this forward lip serves to bind and hold the receptacle against the rear wall with its edge 15 resting upon the inturned lip 14.

When it is desired to restore this inner receptacle to its normal position within the outer casing, it is only necessary to bend back this supporting lip parallel with the plane of its rear wall, which will permit 85 the receptacle 11 to be pressed back into position in the outer casing to permit the closing of the cover 18 and facilitate shipping.

The device is extremely simple and practical in construction and effective in its 90 operation, and by its use the goods may be readily and effectively displayed.

The foregoing description is directed 95 solely towards the construction illustrated, but I desire it to be understood that I reserve the privilege of resorting to all the mechanical changes to which the device is susceptible, the invention being defined and limited only by the terms of the appended 100 claims.

I claim:

1. A display box comprising an outer container having an adjustable receptacle therein, one of the walls of said container being 105 provided with an inwardly bendable lip member, the upper edge of which is adapted to be positioned to extend inwardly to support one edge of said inner receptacle in raised position in the container, said lip 110

being adapted to be forced back and held in disengaging position when said receptacle is returned to normal position within the container.

- 5 2. A display box comprising an outer container having an adjustable receptacle therein, one of the walls of said container being provided with an integral bendable lip member cut from the wall thereof, the upper 10 edge of which lip is adapted to extend inwardly to engage and support one edge of said inner receptacle when set on an incline in said container, the opposite wall of said container being adapted to yield outwardly 15 under pressure of the adjacent wall of the inner receptacle to permit said inner receptacle to assume a relatively inclined position therein and to cause said receptacle to bind against the rear wall of the container

for holding said receptacle in engagement 20 with said lip.

3. A display box comprising a container having an adjustable receptacle therein, one of the walls of said container being provided with an integral bendable lip member 25 cut from the wall thereof, the upper edge of which lip is adapted to extend inwardly to engage and support one edge of said inner receptacle when set on an incline in said container, said lip being adapted to be forced 30 back into the wall from which it is cut to close the opening therein by the repositioning of said receptacle to normal within said container.

In testimony whereof I affix my signature.

WILLIAM H. JOSLIN.
